UNITED STATES PATENT OFFICE.

WILLIAM VAN LOENEN, OF LOS ANGELES, CALIFORNIA.

HERMETICALLY-SEALED PACKAGE AND METHOD OF MAKING THE SAME.

1,281,722.

Specification of Letters Patent. Patented Oct. 15, 1918.

Application filed October 18, 1917. Serial No. 197,369.

To all whom it may concern:

Be it known that I, WILLIAM VAN LOENEN, a citizen of the United States, residing at Los Angeles, in the county of Los Angeles and State of California, have invented and discovered a new and useful Hermetically-Sealed Package and Method of Making the Same, of which the following is a specification.

10 This invention and discovery relates to preventing the addition of moisture or other substances to or the subtraction of moisture or other substances from substances such as cheese, shaving soap and the like, which are liable to injury by the transference of moisture or other substances to or from the same.

An object of this invention is to provide a cheap, effective and thoroughly sanitary means for perfectly conserving substances that are likely to deteriorate from the action of air or moisture or of bacilli or bacteria, and by means of this invention and discovery I am able to produce a cheaper package for this purpose than has heretofore been produced to the same end, and to produce the same with great ease and convenience. It is commonly known that practical oil, air and water-tight packages may be made of metal and also of glass but that such packages are more or less heavy and rigid and are likely to be expensive if made of metal and frangible if made of glass.

An object of this invention is to provide a water, oil, and airtight package of perfect character and minimum weight, which is not fragile or likely to be easily ruptured, and which is peculiarly adapted for sanitary packages of soft cheese-like products and also of other substances for the market.

40 In this invention and discovery I employ a combination with tin foil of sodium silicate and paper, the paper being united to the tinfoil by the sodium silicate and forming a practically unitary envelop which is wrapped upon the article to be protected, the joints throughout being filled and sealed by the silicate of soda; and the silicate of soda, paper and tin foil completely enveloping the article or substance to be protected.

50 An object of the invention is to provide a cheap sanitary package free from objectionable odors and adapted to prevent the passage of any gases, odor, flavor or aroma to or from the enveloped substance so that

packages of cheese, coffee and other substances having an odor or aroma may be stored in any suitable chamber, as in a food closet or a refrigerator with other substances, as butter or milk, for instance without any liability of contaminating or being contaminated by odors, aromas or effluvia from other contents of the chamber.

The package is adapted for putting up fruit such as raisins, currants, dates and food products which may lose aroma or flavor, or which may be contaminated by communication with odor or bacteria laden atmospheric air.

It is understood that cheese and like substances when packed in this package must be kept at such temperature as will prevent the formation of gases. Otherwise the natural action of the contents of the package at any heat calculated to produce such changes will be likely to occur just the same as though the substance were inclosed airtight in glass or tin.

An object of the invention is to make provision for rapidly and conveniently preparing a sodium silicate coated sheet for receiving the package to be enveloped thereby.

Other objects, advantages and features of novelty may appear from the accompanying drawings, the subjoined detail description and the appended claims.

In the accompanying drawings—

Figure 1 is a perspective view of a package in the first stage of manufacture in accordance with this invention, a portion of one side being torn to expose the wrapped article, and a fragment of the liquid glass coated paper sheet being shown ready for application to complete the package.

Fig. 2 is a transverse section of the completed package indicated at X² Fig. 1.

Fig. 3 is a broken perspective view of the completed package.

Fig. 4 is an enlarged fragmental section more clearly showing an external coating of sodium silicate.

Fig. 5 is an exaggerated fragmentary section analogous to Fig. 2 with paste-board carton.

Fig. 6 is a reduced end elevation of a coating and wrapping board showing a sheet in the process of withdrawal from the coating plate of the wrapping board and inversion upon the wrapping block of said board.

a represents a body of pimento cheese forming the article to be wrapped.

1 is an inner sheet of tin foil or the like, 2 is an outer sheet of paper or the like, 3 5 is the sodium silicate bond uniting the sheets. The sodium silicate is available for use in the form of a fluid paste. In practice a body *a* of the substance to be preserved is first wrapped in the tin foil sheet 1. Then the 10 paper sheet 2 having one surface coated with the fluid sodium silicate 3 is applied with such surface inward on the outside of the tin foil package which is then immediately wrapped in said coated sheet and the ends 15 of the paper wrapper thus formed are folded over and before they are so folded over, fluid sodium silicate is applied to all the exposed edges of all the folds where the same are to contact with the package walls so as 20 to entirely close the envelop thus formed and make it integral and practically seamless.

The sodium silicate thus forms an impermeable coating for the tin foil, and an 25 impermeable bond between the tin foil inner sheet of the package and the paper outer sheet.

By the combination thus produced the body is inclosed in a seamless envelop and 30 the passage of moisture, grease, oil or air through the walls of the package is prevented. The package thus formed has a tough flexible integral seamless integument impermeable to air, moisture, oil or grease, 35 and said integument is composed of thin layers of metal, glass and paper perfectly bonded together and devoid of any passage or communication between the inclosed body and the exterior.

40 The superposed layers of tin foil, flexible glass and paper are thus made to constitute an integral structure having a paper coat.

If desired to protect the outside paper coat from the effects of moisture and to doubly seal the package, an external coating 4 45 of silicate of soda may be applied which quickly loses its fluid consistency and forms a flexible glass coat.

After the packages have thus been produced they may be inclosed in pasteboard 50 cartons 5 or in sheet metal boxes or other contrivances to protect the walls of the package against injury from rough-handling or sharp-pointed instruments.

55 It is understood that the invention is broad enough in scope to include a package composed of an inner envelop of metallic sheet material and an outer envelop of fibrous sheet material formed upon the inner envelop and bonded thereto by silicate of soda which entirely envelops the inner envelop; the two envelops being bonded together so as to constitute practically a single envelop, though formed successively.

65 It is important that the sodium silicate

be smoothly and evenly applied to one face of the wrapper and a feature of my discovery and process includes the steps by which the sheet is made ready.

In carrying out this process a wrapping 70 board 6 is provided with a raised block 7, and behind said block, with a glass surface 8. The operator, standing in front of the block and board and reaching over the block, will apply a coating 9. This is done 75 of fluid sodium silicate to the glass surface 8, and will then coat each sheet just before using the same, by applying such sheet with one face downward upon the sodium silicate coating 9, and then immediately applying 80 force to an edge of the sheet to pull it away from the glass surface, thus stripping the sheet from off the coating 9 by taking hold of the farther corners 10 of said sheet and drawing the sheet over the corner 11 of the 85 raised block and thus bringing it coated side up, onto the top face 12 of the block; whereupon the package 1, previously formed, will be laid on the sodium silicate coating 3 of the coated sheet of paper 2. Thereupon the 90 wrapping will be performed as above described.

By this last described step in the process of preparing this package it is made possible to rapidly coat the sheet evenly and 95 smoothly with sodium silicate, without smearing the surface that is to be outside when the package is completed.

I claim:

1. A package comprising a wrapper of tin 100 foil inclosing a substance to be preserved and an outside wrapper of paper united to the tin foil by sodium silicate and having its ends folded and sealed air-tight with material adapted to prevent the passage of moisture 105 through the joints.

2. The method set forth of producing a package which consists in first forming an envelop of sheet material about a body to be inclosed inside the package, then forming a 110 second envelop of sheet material inclosing the first envelop and bonding the outer envelop to the inner envelop by silicate of sodium.

3. The method set forth of supplying the 115 coated sheet for wrapping a package, which consists in coating a glass surface with sodium silicate, applying a sheet of paper to the coated surface and then applying force to an edge of the paper sheet to pull it away 120 from the glass surface, thus stripping the sheet from the coated surface and then turning such sheet upside down on a higher surface to receive the body to be wrapped.

4. The method set forth of producing a 125 package which consists of wrapping in a tin foil wrapper a body of a substance to be preserved; coating one surface of a sheet of paper with sodium silicate; wrapping the sodium silicate coated paper entirely around 130

the tin foil enveloped package and allowing the sodium silicate to bond the paper and the tin foil together; folding the ends of the paper at the ends of the package and coating the exposed edges of the folds with sodium silicate, where the same are to contact with the package walls, then such edges are pressed home, thereby bonding the paper

and the tin foil wrapper of the package together at the ends of the package.

10

In testimony whereof I have hereunto set my hand at Los Angeles, California, this 5th day of October, 1917.

WILLIAM VAN LOENEN.
